Primary Examiner — Jae Liang*Assistant Examiner* — Anthony Vincent Rotolo(74) *Attorney, Agent, or Firm* — QUICKPATENTS, LLC; Kevin Prince(57) **CLAIM**

The ornamental design for a pumpkin lid light mount, as shown and described.

DESCRIPTION

FIG. 1 is a perspective view of a pumpkin lid light mount, showing my new design;

FIG. 2 is an enlarged top perspective view thereof;

FIG. 3 is a front elevational view thereof;

FIG. 4 is a rear elevational view thereof;

FIG. 5 is a right-side elevational view thereof, the left-side elevational view being a mirror image thereof;

FIG. 6 is a top plan view thereof;

FIG. 7 is a bottom plan view thereof; and,

FIG. 8 is a bottom perspective view thereof.

The pumpkin and battery-operated light shown in broken lines in FIG. 1 depict environmental matter and form no part of the claimed design.

1 Claim, 8 Drawing Sheets(56)
